[57] **CLAIM**

The ornamental design for a greeting card album, as shown and described.

DESCRIPTION

FIG. 1 is a front elevational view of a greeting card album showing my new design in an open condition; the rear being flat, plain and unornamented;

FIG. 2 is a left side elevational view of the album with a pre-cut page only in the open position, the right side being a mirror image thereto;

FIG. 3 is a left side elevational view of the album with a perforated page only in the open position; and,

FIG. 4 is a top and right front perspective view of the album with all of the pages in the open position.
